INDOOR TELEVISION ANTENNA

Marvin P. Middlemark, 99-05 63rd Drive,
Rego Park, Queens, N.Y.

Filed June 14, 1962, Ser. No. 70,548

Term of patent 14 years

(Cl. D26—14)

FIGURE 1 is a front perspective view of an indoor television antenna showing my new design;
FIGURE 2 is a front elevational view thereof; and
FIGURE 3 is a side elevational view thereof.
The dominant portions of my design reside in those portions shown in full lines.

I claim:

The ornamental design for an indoor television antenna, as shown and described.
